(57) **CLAIM**

The ornamental design for a headphone, as shown and described.

DESCRIPTION

FIG. 1 is a front elevational view of a headphone showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a second perspective view thereof;

FIG. 9 is a third perspective view thereof;

FIG. 10 is a fourth perspective view thereof;

FIG. 11 is an enlarged view of an enclosed portion of the headphone labeled 11 in FIG. 1;

FIG. 12 is an enlarged view of an enclosed portion of the headphone labeled 12 in FIG. 1;

FIG. 13 is an enlarged view of an enclosed portion of the headphone labeled 13 in FIG. 3;

FIG. 14 is an enlarged view of an enclosed portion of the headphone labeled 14 in FIG. 4;

FIG. 15 is an enlarged view of an enclosed portion of the headphone labeled 15 in FIG. 7;

FIG. 16 is an enlarged view of an enclosed portion of the headphone labeled 16 in FIG. 7;

FIG. 17 is an enlarged view of an enclosed portion of the headphone labeled 17 in FIG. 8; and,

FIG. 18 is an enlarged view of an enclosed portion of the headphone labeled 18 in FIG. 8.

The dashed broken lines shown in FIGS. 1-2, 7-8, and 9-10 depict portions of the headphone that form no part of the claimed design. The dash broken lines shown in FIGS. 1, 3-4, and 7-8 enclosing portions illustrated in enlargements in FIGS. 11-18 form no part of the claimed design.

1 Claim, 18 Drawing Sheets
